COMBINED TUB AND WHIRLPOOL CIRCULATOR

Henry J. Talge, Kansas City, and Herbert D. Goldsmith,
Independence, Mo., assignors to The Songrand Corporation,
Kansas City, Mo.

Filed Jan. 21, 1971, Ser. No. 108,695

Term of patent 14 years

Int. Cl. D24—04

U.S. Cl. D33—1

Fig. 1.

Fig. 2.

Fig. 3.

Fig. 4.

FIG. 1 is a top plan view of a combined tub and whirlpool circulator showing my new design;

FIG. 2 is a side elevational view, the other side being substantially the same;

FIG. 3 is a bottom plan view;

FIG. 4 is an end elevational view, taken from the right hand end of FIG. 1;

FIG. 5 is a sectional view taken along line 5—5 of FIG. 1 in the direction of the arrows, and

FIG. 6 is an end elevational view from the opposite end of FIG. 4.

We claim:

The ornamental design for a combined tub and whirlpool circulator, as shown and described.
